Primary Examiner — Christian P. McLean*Assistant Examiner* — Adam C Mager(74) *Attorney, Agent, or Firm* — Larson & Larson, P.A.;
 Justin P. Miller; Frank Liebenow(57) **CLAIM**

I claim the ornamental design for a golf cart cover, as shown and described.

DESCRIPTION

FIG. 1 is a perspective view of a golf cart cover showing my new design;

FIG. 2 is a front elevation view thereof;

FIG. 3 is a back elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a view showing the golf cart cover in use;

FIG. 9 is a view showing the roof of the golf cart cover folded down without side walls; and,

FIG. 10 is a view showing the roof of the golf cart cover folded up without side walls.

The evenly dashed, closely-spaced broken lines on the golf cart cover illustrate stitching and form part of the claimed design. The remaining broken lines in FIGS. 8-10 illustrate environmental structure and form no part of the claimed design.
